UNITED STATES PATENT OFFICE.

DANIEL J. SCANLAN, OF ST. LOUIS, MISSOURI.

DRAFT REGULATOR.

Application filed October 27, 1923. Serial No. 671,081.

To all whom it may concern:

Be it known that I, DANIEL J. SCANLAN, a citizen of the United States, residing at the city of St. Louis, in the State of Missouri, have invented certain new and useful Improvements in Draft Regulators, of which the following is a specification.

One of the objects of this invention is to control automatically the combustion within 10 a furnace or the like.

This invention is particularly applicable to hot-air furnaces and another object is to regulate automatically the supply of cold air into the hot-air chamber of a hot-air 15 furnace, while simultaneously regulating the combustion.

A further object is to provide means for manually adjusting the automatic combustion-controlling means, whereby a subnormal 20 temperature may be maintained at certain times as desired, as for instance, at night for safety purposes. These manual adjustments do not, however, affect the normal operation of the means for controlling 25 the supply of cold air into the hot-air chamber.

Other objects and advantages will be apparent as the description proceeds.

In the accompanying drawings forming 30 part of this specification, in which like numbers of reference denote like parts wherever they occur,

Figure 1 is a fragmentary front elevation of a hot-air furnace to which this invention 35 has been applied;

Figure 2 is a side elevation of the same; and

Figure 3 is a transverse sectional view 40 through a hot-air pipe and showing a thermostat located therein and with its external connections.

A thermostat 1 is preferably located in one of the hot-air pipes 2, and for that purpose suitable means of support must be provided, such, for instance, as the hanger 3 suitably attached at its ends 4 to the interior of the said pipe 2 and preferably supported by any suitable support 5.

The thermostat 1 is a hollow diaphragm 50 and contains a liquid, preferably water, that is readily expandable or contractible with the increase or decrease of heat of the adjacent hot air flowing through the pipe 2. This diaphragm 1 is preferably made of 55 copper or other suitable material arranged in pleats 6, so that when in its contracted

form its longitudinal extension is materially less than when it is distended by the expansion within it of its liquid contents. When distended, the pleats 6 may be almost ironed 60 out, so to speak; but in its contracted form the pleats lie upon each other. This alternate contraction and distention resembles an accordion.

Diaphragm or thermostat 1 is held in 65 place upon hanger 3 by lugs 7 or other suitable means. A tubular guide 8 is secured to a rod 9, upon one end of which is preferably attached a plate 10 in inner contact with or attached to some part of the diaphragm 70 1. By this means, when diaphragm 1 expands, plate 10 and rod 9 are pressed outward to the furthest position shown in full lines in Figure 3, rod 8 moving through opening 11 in pipe 2; but when diaphragm 1 contracts gravity and spring 12 cause the lowering of rod 8 and plate 10 to the inner dotted position. Upon the other end of rod 9 is mounted a block 13, which in Figure 3 is shown in full-line and dotted-line positions, according to whether the diaphragm 80 1 is expanded or contracted.

A lever 14 is pivoted at 15 to a bracket 16 preferably mounted upon the outside of pipe 2. Lever 14 extends in one direction 85 in juxtaposition to block 13 and has secured thereto a pin 17 which engages a horizontal slot 18 in the block 13. Further towards the end of this extension of the lever 14 are a series of apertures 19, for receiving a hook 20 of a weight 21. The other end of lever 14 is provided with a hook or finger 22, adapted to fit in any one of the holes 23 in regulation plate 24. That moment of lever 14 due to the weight 21 may be varied by changing the hook 20 from one to another of the holes 19, thereby securing the most favorable position for the weight 21 that is necessary to properly balance the weight 90 of the regulation plate 24 and its associated 95 parts and assist the spring 12 in contracting the diaphragm 1.

The lower end 25 of regulation plate 24 is connected by a chain 26 to the draft-door 105 27, pivoted at 28 to the ash-door 29 of the furnace 30. The upper end 31 of regulation plate 24 is connected by a chain 32 to the check-draft door 33, pivoted at 34 to the chimney pipe 35. Chain 32 is supported by rolls 36 in hangers 37, which are secured to 110 the ceiling 38.

A chain 39, connected at 40 to the lever

14, passes over rolls 41, in hangers 42, secured to the ceiling 38, and connects at its other end 43 with lever 44, which operates damper 45 pivoted at 46 in cold-air intake-pipe 47, which leads to the exterior of the building.

The chains 26 and 32 are of such respective lengths as to be just taut when draft-door 27 and check-draft door 33 are simultaneously in closed positions, as shown in Figure 2; and during normal operation this condition obtains with the regulation plate 24 at approximately the middle of its stroke, and with lever 14 substantially horizontal, and connected to the middle of plate 24, as shown in full lines in Figure 2, and with the thermostat 1 at the middle of its stroke. In this position, also, cold-air damper 45 is open half-way, the weight of lever 44 being sufficient to overcome the friction encountered in operating the damper 45, and to keep the chain 39 taut, as indicated in full lines in Figure 2. The weight of the doors 27 and 33 is sufficient to close them whenever permitted by the slackening of their respective chains 26 and 32.

The mode of operation of this device will now be described.

When the diaphragm 1 expands, the rod 8 is pushed outwardly and likewise the block 13. This causes lever 14 to rock on pivot 15, whereby the end bearing hook 22 is depressed, thus allowing plate 24 and chain 26 to descend. When the plate 24 has descended through a certain portion of its stroke, the draft-door 27 is brought to its closed position, as shown in Figure 2, thus cutting off the supply of air to the fire. In this position the check-draft door 33 is still

closed. This is important, as the check-draft door must not be opened until the supply of air to the fire has been cut off. In the meanwhile, damper 45 has opened half-way from its closed position by the pull on the chain 39, admitting a limited supply of cold air into the hot-air chamber.

As the diaphragm 1 continues to expand, chain 26 becomes slack, and the check-draft door 33 is opened by the pull on the chain 32. Simultaneously damper 45 has been opened completely by the pull of the chain 39 thereon. This action simultaneously checks the draft at the chimney, and, also, admits more cold air from outdoors through pipe 47 into the furnace 30. All of the foregoing operations tend to retard combustion and cool the furnace.

When the furnace cools, the temperature decreases in the pipe 2 and this results in the contraction of the diaphragm 1. This results in the lowering of rod 8 and block 13, whereby lever 14 rocks upon pivot 15, automatically elevating hook 22 and plate 24, and partly closing the damper 45 and entirely closing the check-draft door 33; and

taking the slack out of chain 26. As the diaphragm 1 continues to contract, plate 24 is elevated still more, whereby draft-door 27 is automatically opened by the rising chain 26, thus re-establishing the draft through the fire; and chain 39 recedes toward the damper 45, allowing the weight of the lever 44 to entirely close the damper 45. The furnace 30 is thus caused to give forth more heat, which eventually, when needed again, expands thermostat 1, and in succession performs a repetition of the closing of the draft-door 27 and the opening of check-draft door 33 and damper 45.

So far the description of the operation has reference only to the normal functioning of this device. It may be desirable for certain reasons to cause the device to function abnormally at times. For instance, at night, it is preferable to let the fire burn slowly, for purposes of safety as well as for the purpose of lowering the temperature. To accomplish this, it is merely necessary to insert the hook 22 of lever 14 into the highest of the holes 23, so that the regulating plate 24 is lowered from its normal position relatively to lever 14, so much so that chain 26 can never become tight enough to open the draft-door 27, irrespective of the operation of the thermostat 1. However, the functioning of check-draft door 33 is not prevented under these circumstances, but its action is advanced in time so that it begins to check the draft before the furnace has acquired the heat which is necessary to actuate the door 33 under normal conditions. Also, because of the lowering of plate 24, door 33 will open further than under normal conditions if the furnace becomes very hot. Chain 39 being directly connected to the lever 14, the normal regulation of the supply of cold air by the damper 45 is not affected by adjusting the plate 24 relatively to the lever 14, so that a given amount of cold air is always admitted to a given temperature, under both normal and abnormal settings of the plate 24 relatively to the lever 14.

Having thus described this invention, I hereby reserve the benefit of all changes in form, arrangement, order, or use of parts, as it is evident that many minor changes may be made therein without departing from the spirit of this invention or the scope of the following claims.

I claim:

1. The combination with a hot-air furnace provided with a hot-air pipe, of a thermostat located in said hot-air pipe in spaced relation to the body of the furnace, means directly operated by the said thermostat for controlling the supply of cold air to the air-heating chamber of the said furnace, and separate means adjustable relatively to the said thermostat and operated

thereby for controlling the draft through the fire.

2. The combination with a hot-air furnace provided with a hot-air pipe, of a 5 thermostat located in said hot-air pipe in spaced relation to the body of the furnace, a lever actuated thereby, means connected to the said lever for controlling the supply of cold air to the air-heating chamber of 10 the said furnace, a member adjustably connected to the said lever, and means actuated by the said member for controlling the draft through the fire.

3. The combination with a hot-air furnace provided with a hot-air pipe, of a 15 thermostat located in said hot-air pipe in spaced relation to the body of the furnace, a lever actuated thereby, a flexible member connecting the said lever with the damper 20 controlling the supply of air to the air-heating chamber of the said furnace, a member adjustably connected to the said lever, and a second flexible member connecting the said adjustable member with the draft- 25 door of the furnace.

4. The combination with a hot-air furnace provided with a hot-air pipe, of a thermostat located in said hot-air pipe in spaced relation to the body of the furnace, 30 a lever actuated thereby, a flexible member connecting the said lever with the damper controlling the supply of air to the air-heating chamber of the said furnace, a mem-

ber adjustably connected to the said lever, and a second flexible member connecting 35 the said adjustable member with the check-draft door of the furnace.

5. The combination with a hot-air furnace provided with a hot-air pipe, of a 40 thermostat located in said hot-air pipe in spaced relation to the body of the furnace, a lever actuated thereby, a flexible member connecting the said lever with the damper controlling the supply of air to the air-heating chamber of the said furnace, a member 45 adjustably connected to the said lever, a second flexible member connecting the said adjustable member with the draft-door of the furnace, and a third flexible member connecting the said adjustable member with 50 the check-draft door of the furnace.

6. The combination with a hot-air furnace provided with a hot-air pipe, of a thermostat located in said hot-air pipe in spaced relation to the body of the furnace, a lever actuated thereby, a chain connecting the said lever with the damper controlling the supply of air to the air-heating chamber 55 of the said furnace, a chain connecting the draft-door with the check-draft door and a plate borne by the said chain and having a plurality of holes for engaging the end of the said lever.

In testimony whereof I hereunto affix my signature.

DANIEL J. SCANLAN.
